ADRIANUS ANTHONY WILTON VAN REEDE, CORNELISZON, OF PIJNACKER,
NETHERLANDS.

STEAM OR OTHER FLUID ENGINE.

Application filed June 24, 1926, Serial No. 118,284, and in Great Britain June 26, 1925.

- The invention relates to steam or other fluid engines which work on the uniflow principle, and more especially to engines in which a number of cylinders are arranged round a main shaft, the pressure on the pistons being transferred by stems or push rods attached to them to a swash-plate which is keyed on the shaft, as described in the specification of my prior British Patent No. 218,061 of July 3, 1924. Such engines have hitherto been constructed with cylinders of the same diameter and piston stroke, resulting in needlessly great steam consumption since there is but little change of steam load compared with the required power output. The advantages of the uniflow principle are thus lost.
- The object of the present invention is to provide an engine in which these disadvantages are overcome.
- In an engine constructed according to the present invention the advantages of the uniflow principle are fully maintained, the steam consumption being less than that of other engines. The diameters of the several cylinders and the strokes of the pistons differ, thus allowing the steam or other working fluid to expand as much as may be desired. In consequence of this arrangement it is necessary to provide a suitable valve to effect the admission and exhaust of the working fluid into or from the different cylinders. This valve is a main feature of the present invention.
- Working fluid passes through ports to and from the cylinders through a conical valve. This valve is made in two or more coaxial and partly concentric parts which are mounted on the same actuating shaft and have a relative angular adjustment through a few degrees so as to regulate the times of admission and cut-off. This conical valve is mounted in a correspondingly shaped seat in a cylindrical bush or sleeve which is rotatable in a cylindrical chamber situated between the cylinders. This sleeve can be turned for forward or reverse driving by a handle, and its spindle is so proportioned that the end pressure upon it and upon the valve is balanced. At the end of the stroke the fluid, having done its work, for example, in the smallest cylinder, is exhausted on the uniflow principle through a port which is uncovered by the piston to the receiver of the second or larger cylinder, but in addition to this it may be exhausted in part into this same receiver by auxiliary valves.
- This prevents excessive back pressure in the cylinder on the return stroke. The same operations may take place in the succeeding cylinders however many stages of expansion there may be. The last cylinder discharges in like manner both in accordance with the uniflow principle and also through extra valves and ports in the admission valve into a receiver of its own.
- In the accompanying drawings, which illustrate the invention, Figure 1 is a vertical part section along the line L—M, Figure 3; Figure 2 is a horizontal part section along the line M—N, Figure 3; Figure 3 is a transverse section, each quadrant corresponding to a section on the lines A—B, C—D, E—F and G—H, of Figures 1 and 2; Figure 4 is a front view; Figures 5 to 10 inclusive are detail views of the admission valve and of the bush or sleeve in which it is seated; and Figures 11 and 12 show different ways of arranging the cylinders, indicating how the piston strokes may be made to differ in order to obtain the necessary cubic capacity for the expansion of the working fluid together with the least difference in the relative diameters of the cylinders.
- 1 is a fixed casing in which are mounted cylinders 2^a, 2^b, 2^c, 2^d, containing pistons 3. In this particular case there are four cylinders arranged in two pairs, each pair consisting of a small and a large cylinder working in series and having different lengths of stroke. The cylinders of equal size work in parallel but in opposite phase. The front ends of the pistons carry thrust rods 4 rotatably mounted in them and provided with thrust bearings as shown and as described in my former specification. The rods 4 carry shoes 6 which bear against a swash-plate 5 which is keyed as shown at 7 on a main shaft 8. The shoes on the thrust rods 4 are inclined to the rods at the same angle as the swash-plate is inclined to the shaft 8. The rods 4 turn as the swash-plate turns, and the shoes thus always have surface contact with the plate. The shaft is supported at 9 and 10 by ball bearings 11, 12 and 13.
- Admission, distribution and exhaust of working fluid are effected by a conical valve made in two parts 14 and 15. In the present case there are two parts only, but there may be more. This valve has its seating in the coned interior of a bush or sleeve 16 whose

exterior is cylindrical and has its seating in the interior of a sleeve 29 which is concentric with the main shaft. The bush 16 has a spindle 17 carrying a handle 18 by which it can be set for forward or reverse driving. The valve sections 14 and 15 are adjustably secured relatively to one another and to a spindle 30, by a set screw 31. The spindle 30 is a continuation of the shaft 8 which drives it through a squared head and socket 32. The object of making the valve sections 14 and 15 adjustable is to provide for adjustment of the times of admission and cut-off. Means for effecting this adjustment are shown in Figure 6.

The bush 16 is adjustable for ahead or astern working by a spindle 17 and handle 18. 19 indicates a main inlet for the working fluid and the channels connected therewith. 20, 201 and 202 are high pressure fluid inlets, the first of which is in the wall of the small cylinder 2^a, the second in the bush 16 and the third in the valve section 14. 21^b is an admission port in the wall of the large cylinder 2^b, and 211 is an admission port in the valve section 15, which registers with 21^b for admitting fluid to the cylinder 2^b as the valve rotates. 25 is an exhaust port of which there are two branches, one for registration at the proper time with the port 20, and the other for registration with the port 21^b. 22 and 23 are the main exhaust ports in the cylinder walls. 26 are small auxiliary exhaust valves leading to the receiver 24, which conduct fluid from the exhaust port 23 in the high pressure cylinder 2^a when the compression becomes excessive. 27 is the main exhaust chamber and 28 the main exhaust outlet. 33 is a live steam inlet to the receiver 24, used when starting the engine.

Figure 1 shows the position at the end of the pressure stroke of the piston in the cylinder 2^a. At the commencement of this stroke the ports 20 and 202 are in register and working fluid is delivered to the cylinder 2^a from the chamber 19 through the section 14 of the distributing valve. By the end of this stroke the distributing valve occupies the position shown, and the fluid is exhausted through the port 23 into the receiver 24. Excess pressure on the return stroke is exhausted into the receiver through the valves 26.

Figure 2 shows the commencement of the power stroke of one of the large cylinders. Fluid from the receiver 24 is entering the cylinder 2^b through the port 21^b in the cylinder, the port 212 in the bush 16 and the port 211 in the valve section 15. The exhaust takes place through the port 22. Excessive pressure due to compression on the return stroke is relieved by valves 26 and discharged into the receiver 24.

The diameter of the spindle 17 is such that the axial fluid pressures on the conical valve 65 and seat are balanced. This construction

may also be applied to engines of the type described in which the cylinders and stroke are of the same dimensions.

The operations above described may obviously be repeated in any number of cylinders in succession. Figures 11 and 12 are diagrammatic sections of arrangements in one of which three cylinders of different sizes and strokes are used, and in the other four cylinders. 70 75

Having now particularly described and ascertained the nature of my said invention and in what manner the same is to be performed, I declare that what I claim is:—

1. A steam or other fluid pressure engine 80 acting on the uniflow principle, comprising a rotatable shaft, a swash-plate secured upon the shaft, and groups of cylinders arranged about said shaft, said cylinders having pistons, piston rods operatively associated with 85 said swash-plate, the cylinders and pistons of a group being of different diameters and the pistons having a different length of stroke, to enable the working fluid to pass through the cylinders in succession and to expand progressively down to its final pressure, and a valve for distributing motive fluid to said cylinders, arranged coaxially of said shaft, said valve comprising a plurality of coaxial sections having registrable ports, said sections being relatively adjustable to vary admission and cut-off, said valve being externally cone-shaped, and a sleeve having a correspondingly shaped seat for said valve, said sleeve having a spindle and actuating handle 90 for reversing. 95

2. A steam or other fluid pressure engine 100 acting on the uniflow principle, comprising a rotatable shaft, a swash-plate secured upon the shaft, and groups of cylinders arranged about said shaft, said cylinders having pistons, piston rods operatively associated with 105 said swash-plate, the cylinders and pistons of a group being of different diameters and the pistons having a different length of stroke, to enable the working fluid to pass through the cylinders in succession and to expand progressively down to its final pressure, and a valve for distributing motive fluid to said cylinders, arranged coaxially of said shaft, 110 said valve comprising a plurality of coaxial sections having registrable ports, said sections being relatively adjustable to vary admission and cut-off, said valve being externally cone-shaped, and a sleeve having a correspondingly shaped seat for said valve, said sleeve having a spindle and actuating handle 115 for reversing, said valve being of the balanced type. 120

3. A steam or other fluid pressure engine 125 acting on the uniflow principle, comprising in combination a rotatable shaft, a swash-plate secured upon the shaft, a plurality of cylinders arranged operatively with respect to said swash-plate, pistons working in said 130

cylinders, piston rods which press upon the swash-plate, thus causing the shaft to rotate, said cylinders being of different diameters and the pistons having different lengths of stroke to enable the working fluid to pass through the cylinders in succession and to expand progressively down to its final pressure, and a valve for distributing motive fluid to said cylinders, arranged coaxially of said shaft, said distributing valve being provided with auxiliary ports communicating with said cylinders and auxiliary valves controlling said ports for relieving the cylinders of excess compression on their return strokes.

15 4. A steam or other fluid pressure engine acting on the uniflow principle, comprising in combination a rotatable shaft, a swash-plate secured upon the shaft, a plurality of cylinders arranged operatively with respect to said swash-plate, pistons working in said cylinders, piston rods which press upon the swash-plate, thus causing the shaft to rotate, said cylinders being of different diameters and the pistons having different lengths of stroke to enable the working fluid to pass through the cylinders in succession and to expand pro-

gressively down to its final pressure, said piston rods being rotatable relative to the pistons, and flat shoes on said piston rods bearing against said swash-plate.

5. A steam or other fluid pressure engine acting on the uniflow principle, comprising a rotatable shaft, a swash-plate secured upon the shaft, and groups of cylinders arranged about said shaft, said cylinders having pistons, piston rods operatively associated with said swash-plate, the cylinders and pistons of a group being of different diameters and the pistons having a different length of stroke, to enable the working fluid to pass through the cylinders in succession and to expand progressively down to its final pressure, and means supplying motive fluid to the groups in such sequence as to enable them to work in parallel but in different phase, said piston rods being rotatable relative to the pistons, and flat shoes on said piston rods bearing on said swash-plate.

30 35 40 45 In testimony whereof I affix my signature.

ADRIANUS ANTHONY WILTON van
REEDE CORNELISZON.
